CARL R. WALLER, OF TRENTON, NEW JERSEY, ASSIGNOR TO DE LAVAL STEAM TURBINE COMPANY, OF TRENTON, NEW JERSEY, A CORPORATION OF NEW JERSEY

CONTROL FOR BLOWERS

Application filed May 13, 1929. Serial No. 362,548.

This invention relates to controlling means for blowers particularly adapted to secure proper operation of blast furnace blowers.

In the manufacture of pig iron, it is highly essential that during blast periods the blowing engine delivers to the furnace a constant amount of air since the proportion of oxygen must be kept very close to a fixed amount relative to the ore and lime in the furnace. Accordingly, blast furnace blowers have been equipped with governors adapted to maintain a constant volume of air independently of variations in pressures existing at the furnace. Such governing arrangement is made adjustable that the operator may predetermine the constant volume to be delivered in accordance with the demand of the furnace.

After a furnace has been running for a certain number of hours the metal must be drawn. During the drawing period the pressure must be very considerably reduced, inasmuch as the rate of discharge is dependent thereon. It is the practice in some places, for example, to maintain one-half the blast furnace pressure during the casting period after which the pressure is again reduced, the pressure being held substantially constant during each of the latter periods.

Heretofore these lower, substantially constant pressures have been obtained by reducing the speed of the blower and manually operating a large bleeding valve, called a "snorting" valve, near the entrance of the compressed air into the furnace. This procedure has been found quite unsatisfactory by reason of the difficulty in maintaining the pressure sufficiently constant, as is necessary since slight variations in pressure produce large differences in the rate of discharge, which, if increased to any degree, makes the handling of the metal impossible with a given amount of labor and equipment.

Accordingly, it is the broad object of the present invention to provide improved means for controlling a blower whereby either constant volume or constant pressure may be maintained. Detailed objects, as will appear hereafter, relate to the provision of simple interconnections for the controls whereby a

simplified and readily operated blower mechanism is provided.

In the drawings:

Fig. 1 is a diagrammatic view showing the various connections of the control system;

Fig. 2 is a vertical section through the main controlling valve; and

Figs. 3 and 4 are fragmentary views of details.

In the present embodiment of the invention, the controlling means are particularly adapted to provide for the delivery of air at either constant pressure or constant volume from a rotary blower driven by a steam turbine of any desirable type. As disclosed, the turbine is provided with a steam chest 2 in which are located a number of valves 4 serving to control the flow of steam from the steam chest to various sets of nozzles in the ordinary manner, control of speed being efficiently regulated by the successive opening and closing of various valves to secure the admission of steam to definite sets of nozzles. The successive opening and closing of the valves 4 is accomplished through the medium of levers 6 operated upon by cams 8 carried by a cam shaft 10 to open the valves against the pressures of springs which normally tend to hold them closed. Cam shaft 10 is rotated in opposite directions through the medium of oil pressure operating on opposed wings of a rotary piston 12, the oil being admitted to one wing or the other through conduits 14 and 16. Rotation of the piston and cam shaft in the direction indicated by an arrow in Fig. 1 will result in the successive opening of the valves from left to right.

The rotary blower driven by the turbine is indicated by numeral 17.

The control of flow of oil under pressure through conduits 14 and 16 is effected through a valve such as shown in Fig. 2. Conduit 14 opens into an annular port 18 while conduit 16 opens into an annular port 20 arranged within a cylinder in which is mounted for vertical sliding movement a sleeve 22 having openings normally arranged to align with ports 18 and 20 and also having an opening between the said two openings arranged to align with the central port 100.

24, with which communicates a line 26 through which oil is supplied under pressure. Slidable within sleeve 22 is a pilot valve consisting of two pistons 28 and 30 carried by a piston rod 32, the upper end of which is connected to a lever 34 carried by a shaft 36.

10 A collar 38 is secured on the upper end of sleeve 22 and is acted upon by a spring 40 which normally tends to raise the sleeve. This tendency is counterbalanced by the pressure of a lever 42 bearing on the upper end of the sleeve, which lever is pivoted at 44 to the valve casing and is, at its free end, normally urged downwardly by a spring 48 which is of sufficient strength to overcome the tendency of spring 40 to raise the sleeve. The free end of the lever is also connected by a flexible or rigid connection 46 to one 20 end of the lever 50 pivoted on the steam chest, the opposite end of which carries a cam following roller acted upon by a cam 52 mounted on shaft 10.

25 In the operation of the mechanism, a rise of stem 32 will carry the pilot valves 28 and 30 upwardly out of their normal closing alignment with the openings in sleeve 22. As a result, oil under pressure may flow 30 through line 26 and the central ports of the sleeve upwardly within the sleeve and through port 18 into conduit 14, thus causing a motion of cam shaft 10 in the direction of the arrow in Fig. 1. This movement will effect the successive opening of the throttle 35 valves with the resultant increase of speed of the turbine. At the same time, cam 52 will act upon lever 50, raising lever 42 and thus permitting an upward movement of sleeve 22 under the action of spring 40. The openings in sleeve 22 will then be again brought into a closing relationship with pilot valves 28 and 30 so that the flow of oil is cut off and the rotation of shaft 10 limited.

40 The above action of the control valve is of 45 the ordinary type and results in an increase of speed of the turbine without an objectionable floating characteristic. An opposite movement of stem 32 will effect in an 50 analogous fashion the closure of the throttle valves and a decrease in the speed of operation of the turbine.

55 Sleeve 22 also carries a collar 54 with which a piston 56 is arranged to abut if moved upwardly. Piston 56 is normally held downwardly within the casing by means of a spring 58. By the connections as described, sleeve 22 is free to move upwardly independently of the piston, while upward movement of the piston will carry the sleeve upwardly. 60 A conduit 62 enters the cylinder in which piston 56 slides beneath the same, while a small aperture 60 is provided through the piston to permit the normal passage of oil therethrough as long as the oil enters the cylinder at a comparatively low velocity. It

will be understood that all of the overflow oil from the valve and connections is arranged to flow back into a suitable sump from which it is repumped under pressure to the lubricating system and controlling devices of the mechanism.

65 A pump 64 which may be of the ordinary tooth gear construction is driven from the turbine shaft 65 and supplies oil under relatively high pressure through conduit 26. A 70 relief valve 66 communicates with the conduit and permits an overflow, if the normal pressure is exceeded, into a pipe 68 and thence to the bearings of the machine, or other parts to be lubricated. A relief valve 69 set for lower 75 pressure than relief valve 66 prevents the attainment of extremely high pressure in the oil line.

80 The oil line 68 communicates with the upper side of a diaphragm secured to a steam controlling valve 70, forcing the diaphragm in opposition to a spring in a direction to close off the flow of steam through the valve 70. If, for any reason, the pressure of the oil falls so that oil is not delivered through 85 relief valve 66, or is only delivered in insufficient quantity, the pressure above the diaphragm will be insufficient to maintain the steam valve closed against the pressure of the spring. Accordingly, this valve will open 90 and admit steam to a turbine 72 connected with a centrifugal pump 74 which will lift oil from the sump and discharge the same through a discharge line connected to line 26, in which discharge line is located a check 95 valve 76 permitting passage from the centrifugal pump.

100 The devices above described are particularly useful in this device inasmuch as a considerable variation of speed of the turbine 105 will occur. At low speeds, the pump 64 will fail to deliver sufficient oil to properly lubricate the machine and maintain the controlling devices in operative condition. Consequently, 110 it is necessary to bring the auxiliary pump 74 into action to maintain a sufficient pressure. When the turbine is brought up to its normal 115 high speed, the auxiliary pump will be cut out of action and pump 64 will supply all of the oil necessary for the system.

120 A second pump 78 delivers oil through conduit 62 beneath piston 56. At normal speeds of operation of the turbine the oil is delivered at relatively small velocity so that it can pass freely through opening 60 without causing piston 56 to rise. On the other hand, if the turbine acquires an excessive velocity the piston 56 will be raised, carrying upwardly sleeve 22 and thus effecting either a closure of the ports opened by pilot valves 28 and 30 or an opening of the ports 125 so as to permit oil under pressure to flow through conduit 16 and thus effect a rotation of the cam shaft to close the throttle valves of the turbine.

Secured to shaft 36 which, as stated above, carries lever 34 connected to the pilot valves, is an arm 80, the hub of which is provided with an abutment 82 arranged to engage, when moved downwardly as viewed in Fig. 4, an abutment 84 carried by the hub of a lever 86 mounted for free rotative movement about shaft 36. The opposite side of the hub of arm 80 is provided with an abutment 94 which is arranged to engage an abutment 92 formed on a sleeve 90 carried by a shaft 88 when abutment 94 is moved upwardly as viewed in Fig. 4. Shaft 88 is mounted coaxially with, but independently of, shaft 36 and carries at its outer end a lever 96. It will be seen from this construction that arm 80 will positively move arm 86 when it moves in one direction but will not affect the arm when it moves in an opposite direction, the reverse being true of its action upon lever 96.

Situated above arm 86 is a volume governor device comprising a casing in which is secured a diaphragm 98. This diaphragm carries a rod extending downwardly through the casing and connected to a lever 100 having a fulcrum at its other end, as indicated in Fig. 1, and being connected at its free end with lever 86 by a rod 102. A spring 104 is secured at its upper end to lever 100 and at its lower end to a horizontal arm of a bell crank 106, the other arm of which is connected through a suitable linkage with an adjusting lever 108 mounted on a control panel. Movement of lever 108 will result in an adjustment of the tension of spring 104 with a resultant change in operation of the control, as will be later described. Lever 108 is adapted to be maintained in an adjusted position by any suitable means. The casing above and below the diaphragm 98 communicates respectively through conduits 110 and 112 with the throat and entrance of a Venturi tube 114 arranged in the intake of the blower 17. Due to this arrangement, it will be seen that an increase in volume of air flowing into the blower will produce an increase in the difference in pressure on the opposite sides of the diaphragm. Due to the connections, it will be seen that this difference is substantially independent of the pressure existing at the intake, so that the difference in pressure on the diaphragm is dependent primarily on the volume of air flowing into the blower.

A similar diaphragm 115 is mounted in a casing above lever 96 and is similarly connected with a lever 116, the free end of which is connected as indicated at 118 with lever 96. A spring 120 secured at its upper end to lever 116 is connected at its lower end through suitable linkages to an adjustable lever 122, which may be maintained in an adjusted position in any suitable manner so that a predetermined tension may be produced in spring 120. The upper and lower sides of diaphragm 115

communicate respectively through a passage 124 and a conduit 126 with the atmosphere and the compressed air inlet adjacent the furnace. It will thus be seen that movement of the diaphragm is effected by a change in pressure at the furnace.

A rod 128 is received within the bifurcated upper end of arm 80 and is connected to a lever 130 which may be secured in either of two extreme adjusted positions by means of a suitable controlling lever mounted on the control board. The free end of rod 128 is provided with an abutment 132 against which a spring 134 bears, the inner end of the spring abutting against a collar 136 slidably mounted on rod 128. An abutment 138 limits movement of a second spring 140, the opposite end of which abuts a collar 142 slidably mounted on the rod. Collars 136 and 142 are limited in their movements toward each other by means of suitable pins or the like. The bifurcated upper end of arm 80 is provided with a suitable head 144 arranged to selectively abut collars 136 or 142 accordingly as arm 130 is moved to either of its adjusted positions, this movement effecting a compression of one of the springs to correspondingly move arm 80 so that its hub contacts with abutment 84 or 92.

In considering the operation of the device let it be assumed, the machine being at rest, that lever 130 is set as shown in Fig. 1, whereby arm 80 will be moved in a clockwise direction into engagement with arm 86 which will be in its extreme lower position due to the tension on spring 104 and the absence of differences in pressure on the sides of diaphragm 98. Spring 134 will be slightly compressed thereby maintaining the engagement of abutments 82 and 84 in all positions of adjustment. Due to the extreme movement of arm 80, pilot valves 28 and 30 will be in their extreme upper positions, opening communication between line 110 and conduit 14.

If, now, steam is turned on, oil pump 74 will operate, forcing oil into line 26 and thus effecting movement of cam shaft 10 to open the steam valves to their full amount, the opening movement being limited by the upward movement of sleeve 22 to shut off the flow of oil into conduit 14.

As the turbine gains speed, difference in pressure occurs on the sides of the diaphragm 98, resulting in an upward movement of lever 86 which carries arm 80 in a counter-clockwise direction moving the pilot valves downwardly and effecting successive closure of the throttle valves. Equilibrium will be attained when the differential pressure on diaphragm 98 is balanced by spring 104 and the valves are so set as to maintain a constant volume of air entering the blower. It will be seen that this equilibrium po-

sition is dependent on the tension of spring 104, a change in the tension of which, through manipulation of lever 108, will result in an attainment of equilibrium at a 5 different constant volume. Any deviation in the volume entering the blower will result in a compensating change in speed of the turbine as will be obvious.

As was stated above, in the operation of 10 blast furnaces, the constant pressure maintained during the casting is less than the pressure during the blasting. When the constant pressure operation is desired, lever 130 is set so that spring 140 moves lever 80 15 in a counter-clockwise direction against abutment 92 of collar 90. This movement results in a downward movement of pilot valves 28 and 30 with resultant closure of the throttle valves and slowing down of the 20 machine. It will be seen that now the tension of spring 120 determines the equilibrium speed and that changes in pressure will be compensated by change in speed of the 25 blower. The operator may, accordingly, determine the constant pressure of operation by suitable adjustments of lever 122.

For simplicity, levers 86 and 96 have been 30 shown as connected directly to diaphragms 98 and 115. For greater sensitivity, motion multiplying devices of the usual type applied to diaphragm controlling mechanisms may be used to obtain large motions of the levers for slight movements of the 35 diaphragms.

35 While the Venturi tube is shown as located in the intake of the blower or compressor, it will be obvious that it may be located in the discharge.

What I claim and desire to protect by Letters Patent is:

1. In combination with a compressor and driving means therefor, means for controlling the delivery of the compressor, a device operating responsively to the pressure of gas handled by the compressor, a device operating responsively to the volume of gas handled by the compressor, and means for selectively rendering the controlling means subject to actuation by the operation of either the pressure responsive device or the volume responsive device to effect the delivery of compressed gas at either substantially constant pressure or substantially constant volume.

55 2. In combination with a compressor and driving means therefor, means for controlling the speed of the driving means, a device operating responsively to the pressure of gas handled by the compressor, a device operating responsively to the volume of gas handled by the compressor, and means for selectively rendering the controlling means subject to actuation by the operation of either the pressure responsive device or the volume responsive device to effect the delivery of com-

pressed gas at either substantially constant pressure or substantially constant volume.

3. In combination with a compressor, and a driving turbine therefor having valve means for controlling the flow of propelling fluid thereto, liquid operated means for operating the valve means, a valve for regulating the delivery of liquid to said liquid operated means, means for supplying liquid under pressure to the valve, the operation of said supplying means being dependent on the speed of operation of the compressor, auxiliary means for supplying liquid under pressure to the valve when insufficient pressure is produced by the first named supplying means, a device operating responsively to the pressure of gas handled by the compressor, a device operating responsively to the volume of gas handled by the compressor, and means for selectively rendering said valve subject to actuation by the operation of either the pressure responsive device or the volume responsive device to effect delivery of compressed gas at either substantially constant pressure or substantially constant volume.

In testimony of which invention, I have hereunto set my hand, at Trenton, New Jersey, on this 9th day of May, 1929.

CARL R. WALLER.
